BOW SLING

Merle L. Foster, Iowa Falls, Iowa

Filed Mar. 4, 1969, Ser. No. 16,020

Term of patent 14 years

Int. Cl. D22—99

U.S. Cl. D22—99

FIGURE 1 is a frontal perspective view of my bow sling showing my new design;

FIGURE 2 is a top plan view thereof;

FIGURE 3 is a front elevational view thereof;

FIGURE 4 is a side elevational view thereof as viewed from the right-hand side of FIGURE 3;

FIGURE 5 is a rearward elevational view thereof; and

FIGURE 6 is a bottom plan view thereof.

I claim:

The ornamental design for a bow sling, substantially as shown.
